UNITED STATES PATENT OFFICE.

ALEXANDER NYMAN, OF SWISSVALE, PENNSYLVANIA, ASSIGNOR TO WESTINGHOUSE ELECTRIC & MANUFACTURING COMPANY, A CORPORATION OF PENNSYLVANIA.

DIAPHRAGM.

Application filed September 20, 1923. Serial No. 693,783.

My invention relates to diaphragms, having particular relation to diaphragms designed for use in loud speaking telephone devices. It is, however, applicable to other 5 acoustic devices such as microphones, phonographs and the like.

In its broadest aspect, an important object of my invention is to provide a diaphragm whereby sound waves may be faithfully 10 translated into correspondingly modulated electrical energy, and vice versa, without impairing the quality, tone and quantity of the translated energy.

More specifically, another object of my invention is to provide a diaphragm which is characterized by the absence of resonant 15 points and by the fact that the stiffness of the diaphragm, in opposite directions, is substantially the same.

20 A further object of my invention is to provide a diaphragm which is simple in design and construction and which may be readily manufactured by existing automatic machinery with minimum expenditures of time 25 and of money.

The diaphragms of the prior art, for the most part, consist of plain circular discs of some desired material, as, for instance, mica, paper, or iron, depending upon the specific 30 application thereof. Experience has shown that such diaphragms have one resonance frequency for the diaphragm as a whole, and one or more other partial resonant frequencies, the latter depending upon the relative 35 arrangement of such kinks or wavy places as may occur in the surface of the diaphragm.

The foregoing difficulties have been partially overcome in certain prior art diaphragms by impressing upon the diaphragm corrugations in the form of concentric circles. However, it was found that the concentrically disposed corrugations gave rise to harmonics, depending upon their distance 45 from the center of vibration of the diaphragm.

In practicing my invention, the above-mentioned difficulties are avoided by providing the diaphragm with corrugations, the 50 spacing of which is continuously variable with respect to the center of vibration of said diaphragm. Thus, points on the diaphragm of equal radii, but of different an-

gular position may give rise to harmonics of different frequencies which completely or partially balance, all as explained more fully hereinafter.

In one embodiment of my invention, I provide a diaphragm with a plurality or series of concentrically disposed spiral corrugations so arranged as to provide a substantially smooth central portion and an annulus at the periphery thereof, the annulus and the central portion being positioned intermediate the opposite faces of said diaphragm and the corrugations terminating in the central portion and in the annulus in such relation that the diaphragm has an equal stiffness in opposite directions.

Other objects and applications of my invention, as well as details of construction and arrangement, will be apparent more fully hereinafter, when taken in connection with the accompanying description, claims and drawing wherein,

Figure 1 is a transverse sectional view of a dished diaphragm.

Fig. 2 is a top plan view of the preferred embodiment of my invention.

Figs. 3 and 4 are enlarged transverse sectional views of the apparatus shown in Fig. 2, the sectional planes being indicated by the lines III—III and IV—IV, respectively.

Fig. 5 is a view similar to Fig. 2 illustrating a modification in the arrangement of the corrugations, and

Figs. 6 and 7 are enlarged transverse sectional views taken on the lines VI—VI and VII—VII, respectively, of Fig. 5.

In the preferred embodiment of my invention shown in Fig. 2, a diaphragm 1 comprising a circular disc 2 of resilient material is provided with a series of spiral corrugations 3 and 4. The corrugations originate in an annular portion 5 which defines the outer periphery of the diaphragm 1 and terminate in a substantially smooth central portion 6 having a central point 7, the latter being designed to serve as the center of vibration of the diaphragm 1. The series of corrugations 3 and 4 are so pressed into the disc 2 as to position the central portion 6 and the annular portion 5 in a plane substantially midway between the opposite faces thereof.

A characteristic of a pair of spirals, as shown in the drawing, is that points 180°

apart and of equal radii, are on different spirals and of corresponding elevations or depressions. For instance, points *a* and *b*, shown in Fig. 3, which are spaced 180° apart and which have equal radii with respect to the center of vibration 7 of the diaphragm 1, are positioned, respectively, on the series of spiral corrugations 3 and 4 and are of corresponding elevation. Similarly, it is noted that diametrically opposite positioned points *a*¹ and *b*¹, shown in Fig. 4, which are equally spaced with respect to the center of vibration 7, are respectively positioned on the series of corrugations 3 and 4 and are of corresponding depression. Thus, points on the diaphragm 1, which are equally spaced with respect to the center of vibration thereof and which are angularly spaced 180° apart, have corresponding displacements on different series of spirals and, hence, the formation of harmonic circular nodal points is avoided.

It is known that when a force is applied to a dished diaphragm, as shown in Fig. 1, in a direction indicated by arrow "d", the displacement thereof is much greater than when a corresponding force is oppositely applied to the diaphragm in a direction indicated by arrow "e"; that is to say, by reason of the curvature of the diaphragm, the stiffness thereof, in opposite directions, is not equal. This principle is applied in my invention, wherein it may be noted that, in the sectional view shown in Fig. 3 the annular portion 5 and the central portion 6 are dished in one direction; whereas in Fig. 4, which is a sectional view displaced 90° from that of Fig. 3, the annular portion 5 and the central portion 6 are dished in the opposite direction. Hence, it follows that the undesirable effect noted in Fig. 1 is entirely absent in the embodiment of my invention shown in Fig. 2, thereby providing a diaphragm which has an equal stiffness in the two directions.

In Fig. 5 is shown a modification which differentiates over the embodiment of my invention shown in Fig. 2 in the provision of a single spiral groove 8 only, rather than a double spiral groove as previously shown. In this modification, points having equal radii and angularly spaced 180° apart have opposite elevations with respect to a central portion 6' or an annular portion 5' as shown, for instance, by points *f*, *g* and *f'*, *g'*, in Figs. 6 and 7, respectively. In view of the opposite displacement of equally spaced points 180° apart, harmonics at these points are avoided.

While I have shown but two embodiments of my invention, for the purpose of describing the same and illustrating their principle of operation, it is apparent that various changes and modifications may be made therein without departing from the spirit of

my invention. I desire, therefore, that only such limitations shall be imposed thereon as are indicated by the appended claims or as are demanded by the prior art.

I claim as my invention:

1. A diaphragm provided with a plurality of series of spiral corrugations, and also with a substantially smooth central portion disposed intermediate the opposite surfaces of said diaphragm, said series of corrugations terminating in said central portion. 70

2. A reinforced diaphragm, the reinforcement being symmetrically arranged relative to the two faces of the diaphragm whereby equal displacements in the two directions will result from the similar application of equal forces to the two faces. 80

3. A diaphragm provided with a spiral corrugation, the radii of said spiral at diametrically opposite points being such that a harmonic established at one such point substantially cancels that established at the other. 85

4. A diaphragm provided with spiral corrugations, a substantially flat central portion and a narrow annulus at the edge of said diaphragm, said spiral corrugations being so arranged that said diaphragm has an equal stiffness in opposite directions. 90

5. A diaphragm provided with a plurality of series of spiral corrugations so disposed as to leave a substantially flat central portion, said portion being disposed substantially midway between the opposite faces of said diaphragm, said corrugations terminating in said central portion in such relative 100 relation that the stiffness of said central portion in opposite directions is equal. 95

6. A diaphragm provided with a plurality of series of concentrically disposed spiral corrugations so arranged as to provide a substantially smooth central portion and an annulus at the periphery thereof, said annulus and said central portion being positioned intermediate the opposite faces of said diaphragm, said series of corrugations terminating in said annulus and in said central portion in such relation as to avoid a dished condition of the diaphragm. 110

7. A diaphragm provided with a plurality of concentric spiral corrugations, said spirals 115 being such that points at equal distances from the common center on radii that divide 360° into as many equal parts as there are spirals have corresponding elevations or depressions. 120

8. A diaphragm provided with a pair of concentrically disposed spiral corrugations, said spirals being such that points 180° apart and of equal radii have corresponding elevations or depressions. 125

9. A diaphragm provided with a plurality of concentric spiral corrugations so designed that points at equal distances from the common center on radii that divide 360° into twice as many equal parts as there are spi- 130

rals have substantially opposite displacements.

10. A diaphragm provided with corrugations in the form of a double spiral, wherein 5 points 180° apart and of equal radii are on different spirals and of corresponding elevations or depressions.

11. A diaphragm provided with a plurality of series of concentrically disposed spiral 10 corrugations, a substantially smooth central portion and an annulus at the periphery, said annulus and said central portion being positioned intermediate the opposite faces of

said diaphragm, said spirals being of such design that points 180° apart and of equal 15 radii have corresponding elevations.

12. A corrugated diaphragm having a substantially flat portion, axially displaced portions adjacent said flat portion, the displacement being opposite along diameters at 20 right angles to each other.

In testimony whereof, I have hereunto subscribed my name this 14th day of September, 1923.

ALEXANDER NYMAN.
